UNITED STATES PATENT OFFICE.

EARL B. DECKER, OF CLEVELAND, OHIO, ASSIGNOR TO BARTON R. DEMING, OF CLEVELAND HEIGHTS, OHIO.

IRONING MACHINE.

Application filed October 12, 1922. Serial No. 594,179.

The present invention relates to an ironing machine of the type which is primarily intended for household use, although nothing is intended by this statement to indicate 5 that its use may not be more extensive than that indicated.

One of the objects of the present invention is to provide a treadle structure for use in connection with such household ironers 10 which has certain advantages, chiefly among which is the ability to apply substantially equal pressure between the roll and the ironing member when the foot of the operator is placed on the treadle at any part thereof 15 between the ends.

A second object of the invention is to provide a machine of this character in which the table upon which the material to be ironed is fed between the rotating rollers 20 and the ironing member proper, is so pivoted as to be movable above and out of the way of the roll, so as to leave the entire front of the machine open and free where such is desired.

Reference should be had to the accompanying drawings forming a part of this specification, in which Fig. 1 is a perspective view showing the device; Fig. 2 is a rear elevation of a portion of the machine with parts in section; Fig. 3 is a perspective view showing one end of the machine; Fig. 4 is an end elevation showing in dotted lines the optional positions to which certain members may be moved; Fig. 5 is a plan view with portions in section of one end of the machine showing the driving gearing. Fig. 6 is a top plan view of a portion of the construction forming the treadle structure. Fig. 7 is a perspective view showing a ratchet mechanism 40 located at one end of the treadle.

Referring to the drawings, the frame of the machine is composed of end leg members 1, which at their lower ends are provided with casters 2, and these legs adjacent their lower end portions have cross members, such as indicated at 3, which join the respective adjacent legs.

At the upper end these legs are in any suitable manner secured to a platform member 4. All the foregoing is quite usual construction.

Mounted at one end of the platform 4 is a bracket 5 which has a portion that is secured to the platform 4, and a portion which

extends substantially vertically, as indicated 55 at 5^a. This bracket at its upper end supports one end of what I term an ironing member 6. This member is formed with a curved inner surface, as indicated at 6^a, and is a hollow structure within which there is 60 some suitable form of heating element, it being permissible to use either gas or electricity.

In the present instance there is shown gas 65 pipes 7 through which gas may be conducted to be burned inside the ironing member 6.

Associated with the ironing member is a roll 8 which is positioned in front of the curved face 6^a of the ironing member, and 70 is so mounted as to be moved toward and from the ironing member 6.

Extending transversely between the upright 5^a and a second upright 13 at the opposite end of the platform is a shaft 9. This shaft at one of its ends extends beyond the upright 5^a and at the end thereto there is secured a pivoted arm or bracket 10. This bracket is pivotally mounted as indicated at 11, so that it may swing outwardly and away from the roller 8. This bracket is a right angle bracket and at the end of the upstanding arm is provided with a half journal, such as indicated at 10^a, in which rests the 85 end of a shaft 8^a upon which the roller 8 is mounted. The upper half of the bearing 10^a is covered in any suitable manner, as for instance, by means of a cover piece 12. At the opposite end of the machine there is an upstanding member 13 in which the shaft 90 9 is journalled, and secured to this shaft in any desired manner is an arm 14 which at its end has a journal supporting the shaft 8^a upon which the roller is mounted.

It will be seen that if the shaft 9 is caused 95 to rotate, the arm 14 and the bracket 10 will be moved with the shaft 9, and so raise and move the roller 8 toward the ironing member 6. Therefore, oscillation of the shaft 9 serves to raise the roller into engagement with the 100 ironing member 6 or to move the roller slightly away from that ironing position.

By virtue of the fact that the roller 8 is mounted at one end upon the pivoted bracket 10, it is possible to release the end of the 105 roller by removing the cover member 12 lifting the shaft 8^a out of its bearing in the bracket 10, and swinging the bracket away

from the end of the roller 8. This feature of the construction does not form a part of this invention.

For the purpose of operating the shaft 9 there is provided a pair of spaced arms 15 and 16, these arms being fastened to the shaft 9 in any suitable manner. Each arm at its end is connected with a rod member such as indicated at 17.

10 Extending transversely between the rear legs 1 is a rod 18 which is stationary and fixed to the legs 1. Upon this rod 18 is a member which has a sleeve portion 19 with an arm 20 extending from one end thereof, 15 and a longer arm 21 which extends from the other end of the sleeve portion 19. The sleeve portion 19 encircles the shaft 18, but is unsecured thereto, being merely mounted upon the same.

20 These members which have just been described are mounted so that the arm 21 lies at the end of the frame which is formed by the legs 1 and the parts connecting the same and extends from the rod 18 toward the 25 front of the ironing machine. The arm 21 has one end of a spring 22 secured thereto the opposite end of which is secured to the adjacent rear leg 1.

There is a second member having a 30 sleeve shaped portion 19^a, a short arm 20^a, and a long arm 21^a, which is likewise journaled upon the rod 18, and so positioned that the long arm 21^a extends forward toward the front of the machine, 35 and at the end thereof adjacent to that at which the arm 21 is located. One end of a spring 23 is secured to the arm 21^a and the opposite end is secured to the adjacent rear leg 1. These arms 21 and 21^a at 40 their extreme forward ends support a transversely extending foot operated member or treadle 24, which member extends substantially entirely across the front of the ironing machine and between the front uprights 45 or legs 1. At the ends of the treadle there are extending pins, such as indicated at 25 which are journaled in the ends of the arms 21 and 21^a, so that the foot member 24 is pivotally mounted. At each end of the foot 50 operated member 24 and loosely journaled on the pin at each end thereof is a pawl 26 and 27, this pawl being normally urged forward or toward the adjacent leg 1 by means of a spring, such as indicated at 28, 55 which normally lies behind each pawl. On the inner side of each of the front legs 1 there is secured a rack having ratchet teeth 29 which is so positioned as to be engaged by the adjacent pawl, and under the action 60 of the spring 28 each pawl will normally engage with the ratchet teeth before mentioned. Each pawl has upon the side thereof which is toward the foot operated member a projection 26^a and this projection is in 65 line to be engaged by a projection 23^a which

is carried at the end of the foot engaging member, so that as the foot engaging member is rocked toward the rear of the ironing machine, the projection 23^a will engage the projection 26^a to throw the particular pawl 70 out of engagement with its ratchet. The construction of the pawls and the arrangement by which they may be released is the same at both ends of the foot operated member 24. 75

It will be noted that when the foot operated member 24 is depressed, no matter to what portion the depressing force is applied to the member 24, it will cause the shaft 9 to be turned, and inasmuch as the 80 shaft 9 is quite rigid it will transmit the turning action which may be applied to it through either the arm 15 or the arm 16, or through both, substantially equally to both ends of the shaft 9, so that the roller 8 will 85 be brought into engagement with the ironing member 6 with practically equal pressure throughout the length of the roller 8.

Moreover, it will be seen that the foot 90 engaging member 24 will be retained in the position to which it may be depressed through the action of the pawls 26 and 27 engaging with their respective ratchets. And furthermore, it will be seen that by a simple pivotal movement of the foot 95 engaging member 24 the ratchets may be released and the roller 9 thereby permitted to move to its nonengaging position.

The foregoing mechanism is extremely 100 simple and rugged, and provides a simple mechanism for moving the roller.

In front of and above the roller 8 is a table 30 which is so positioned that articles which are to be fed between the ironing member and the roller 8 may be conveniently 105 spread out upon this table and properly fed upon the roller 8. This table member at its opposite ends is mounted upon an arm 31 each of which arms is pivotally mounted at the opposite ends of the ironing member 6, as indicated at 32. Each arm 31 is provided with a right angle extending member 33 which is adapted to engage with the ironing member adjacent its upper forward edge, and thus form a limiting stop whereby 110 the table 30 is retained in proper position and prevented from swinging downwardly in front of the roller 8. Each arm 31 is provided with a right angle extending leg 34, and this is so positioned that when the 115 arms and the table 30 are swinging into upright position the member 34 will engage a portion of the outer surface of the ironing member 6 and so prevent the table 120 from moving beyond the desired position. 125

This arrangement is useful inasmuch as it permits the table 30 to be readily moved from in front of the roller member 8 thereby affording free access to the roller when it is desired to change the covering on the 130

roller or where it is desired to insert an article to be ironed, such for instance as a skirt, over the end of the roller, for the purpose of ironing the same or to remove it from the roller.

5 The roller member 8 is rotated, and for this purpose a driven shaft 35 is provided which engages with a gear wheel 36 carried upon a sleeve 37 which is mounted upon the 10 end of the shaft 9 but is unsecured thereto and is free to rotate. Upon the sleeve 37 there is mounted a slidable gear 38 which is splined to the sleeve 37. This gear 38 is moved by a lever 39 so that it may be moved 15 into or out of mesh with a gear 40 which is carried at the end of the shaft 8a upon which the roller 8 is mounted. The particular gearing which is utilized in driving the roller forms no part of the present invention.

Having described my invention, I claim:—

1. In an ironing machine having a supporting frame and a pair of ironing elements one movable toward and from the other, means for actuating the movable element comprising a pair of levers pivoted to swing about a common axis, an operating member pivotally connected at its opposite ends to said levers to rock about a longitudinal axis, and means connecting said levers to said movable element coating locking members on the operating member and frame for retaining said member in a position to which it has been moved, and means 35 operable upon a rocking movement of said operating member for releasing said locking members.

2. In an ironing machine, a supporting frame, an ironing shoe mounted on the 40 frame and extending lengthwise thereof, a rock shaft journaled in the frame beneath the shoe and parallel therewith, arms secured to said shaft adjacent the ends thereof and extending forwardly therefrom, arms secured to said shaft and extending rearwardly therefrom, a roller journaled at its ends in the first mentioned arms, a second shaft parallel with the first and carried by the frame adjacent the bottom thereof, a pair of levers pivoted on said shaft adjacent opposite ends of the frame, each lever having a sleeve portion rotatable on said shaft, a long arm extending from the outer end of the sleeve portion toward the front 55 of the frame and a short arm extending from the inner end of the sleeve portion toward the front of the frame, a rod connecting each short arm to one of the rearwardly extending arms of the rock shaft, and a treadle 60 connected at its opposite ends to the forward ends of the long arms.

3. In an ironing machine, the combination of an ironing shoe and a roller engageable therewith, means for driving the roller, a table normally extending in front of the 65 roller with its inner edge adjacent the top of the roller and pivotally mounted to swing about an axis parallel with that of the roller and at the rear of the roller, said table being swingable about said axis to a position 70 above and to the rear of said roller and shoe.

4. In an ironing machine, a support, an ironing shoe mounted upon said support, a roller mounted upon the support in position to engage with said ironing shoe, means 75 for driving the roller, a table extending in front of the roller, a pair of brackets for supporting the table, said brackets being connected to opposite ends of the table and extending rearwardly past the roller, and 80 means for pivotally supporting the brackets to swing about an axis parallel with that of the roller and at the rear of the roller whereby the table may be swung clear of the roller and shoe.

85 5. In an ironing machine, a support, an ironing shoe mounted upon said support, a roller mounted upon the support in position to cooperate with said ironing shoe, means for driving the roller, a table extending in front of the roller, a pair of brackets, the forward end portions of which are secured to opposite ends of the table, said brackets extending rearwardly past the 90 roller and pivotally mounted to swing about an axis at the rear of the axis of the roller, and means for limiting the swinging movements of said brackets whereby the table may be supported in operative position in front of the roller or in inoperative position 95 above the same and clear of the roller and shoe.

100 6. In an ironing machine, a support, an ironing shoe mounted upon said support, a roller mounted upon the support and engageable with said ironing shoe, means for driving the roller, a table extending in front of the roller, a pair of brackets for supporting the table, said brackets being secured to the table at opposite ends thereof, each of 105 said brackets being pivotally mounted upon the ironing shoe rearwardly of the roller, and stop members carried by each of said brackets and engageable with the shoe to limit the pivotal movements of the brackets 110 whereby the table may be supported in operative position in front of the roller or in inoperative position above the roller and rearwardly of said pivotal connections.

115 In testimony whereof, I hereunto affix my 120 signature.

EARL B. DECKER.
